UNITED STATES PATENT OFFICE.

JAMES C. LEDBETTER, OF BROOKLYN, NEW YORK, ASSIGNOR, BY MESNE ASSIGNMENTS, TO THE PROSPERITY COMPANY, INC., OF SYRACUSE, NEW YORK, A CORPORATION OF NEW YORK.

ELECTRIC GARMENT PRESS.

Application filed July 9, 1924. Serial No. 724,930.

This invention relates to garment pressing machines and more particularly to improved electric garment presses.

An object of the invention is to produce an electric garment pressing machine embodying high temperature steam generating means within one of the pressing members but segregated therefrom, and possessing improved water feed means in connection therewith, as well as improvements in a unitary generating boiler with a steam dome adapted to direct the steam downwardly into a foraminous pressing member.

Electric steam generating instrumentalities have been suggested for pressing machines but have fallen short of usefulness in many particulars; and one of the predominating faults with electric steam generators has been the tendency to try to generate steam with the same heat which heats the working face of the pressing members with the result that a safe working temperature for the face of a pressing member too slowly vaporizes the water to deliver live hot steam at high velocity under pressure to the garment. I adopt a different principle and employ an extremely high temperature which is much too high to heat the pressing members since the cloth would be burned. I concentrate all the heat, as intended for vaporizing the water, into a small high speed flash generator, run the boiler at practically a low cherry red heat which instantly vaporizes the water coming in contact therewith; and to make the plan safe, I suspend the boiler in an insulating air space. The air space insulates the boiler from all parts of the pressing member to prevent undue heat from being communicated from the boiler to the working face of the pressing member. And the air space, in one instance, is the steam spray chamber down into which the steam flows in coursing through the pressing member to reach the garment; and a steam dome is employed to form an air space around the small high temperature boiler, all parts being mounted on a single base and held in spaced relation from the working face of the pressing member.

The accompanying drawings illustrate one embodiment of the invention but it is understood how changes may be made with-

out departing from the principle of the invention.

Figure 1 illustrates an upper fragmentary view of a pressing machine embodying the electric steam generating improvements and showing the water supply means.

Figure 2 illustrates a cross sectional view of a pressing member showing the unitary steam generating element mounted therein.

Figure 3 is a perspective view of the improved steam boiler adapted to vaporize water and deliver steam to the garment being pressed.

Referring further to the drawings for a detailed description of the invention, there is shown a suitable form of pressing machine frame 5 which supports a buck 6. A fulcrum shaft 7 is supported in the frame 70 and carries a pressing lever 8 on the front end of which is mounted a pressing head 9. Any suitable operating mechanism such as a toggle or the like may be employed to swing the lever 8 thereby opening the pressing jaw members 6 and 9. It is understood how both pressing members 6 and 9 may be electrically heated by individual current circuits if necessary.

The improved electric boiler of unitary construction will now be described. One pressing member, as for example the head 9, is made with a large screw-threaded opening 11 into which is mounted a threaded plug 12 which serves to close the opening 85 and which further serves to carry all the parts constituting the steam generating device. Furthermore the plug holds the boiler in mid air so-to-speak thereby providing a surrounding air insulating medium, for the boiler works at high temperature, and thus the air space acts to diminish the heat radiated from the boiler.

The plug 12 is made with a central opening 13, and the electric boiler for vaporizing the water is held centrally in this opening. The boiler comprises a flanged base 14 carrying upstanding spaced insulating walls 15 and 16 between which is placed an annular electric heating element 17 drawing current 100 from lead wires 18. The boiler is cup-shaped and open at the top. The bottom thereof consists of similarly spaced insulating walls with a like electric heating element

disposed thereinbetween and which receives its current from the feed wires 18. The flanged base 14 is provided with brackets 19 which are fastened to the inner wall of the 5 plug opening 13, and the arrangement is such that the open top cup-shaped boiler 15 is held centrally in the plug opening 13, and the bracket 19 being small act as a slow or 10 poor conductor of heat thus tending to 15 serve the heat in the boiler.

A water spray means is employed to atomize the water into the hot cup 15 and comprises a perforated nozzle 21 carried on a feed pipe 22. A pipe connection 23 provides a connection between the passage 24 in 15 the plug and the said pipe 22; and in like manner a pipe 25 conveys water from any suitable source to the plug passage 24 and thence to the atomizing nozzle 21 within the 20 boiler.

A steam dome 27 is disposed over the boiler and the top of the dome deflects the steam downwardly as it issues from the cup. The plug 12 provides a substantial base upon 25 which the dome 27 is anchored. Insulating means may be provided if desired to insulate the hot steam dome 27 from the atmosphere, and to this end a hood 28 is placed over the dome and similarly anchored to the plug 22 30 and thus the hood 28 aids in retaining the heat within the dome. It is desired that the air medium surrounding the boiler in the dome and in the spray chamber be maintained at high temperature in order to prevent 35 condensation of the steam in its downward travel, and this follows by virtue of the large opening 13 in the plug which joins the dome and spray chamber in one continuous air chamber.

40 Any suitable water supply means may be used for the purpose of delivering water to the generating element, but a preferred type resides in a water tank 30 mounted rigidly on the press lever 8 or fulcrum shaft 7 there- 45 by adapting the tank or reservoir to oscillate with the moving press lever. The tube connection 25 hereinbefore described runs from the reservoir 30 to the boiler cup 15. A suitable valve box 31 is included in the pipe 50 line 25 together with a force pump 32 which is adapted to force a predetermined amount of water from the tank 30 to the press head 9. The pump is fitted with a plunger 33 actuated by suitable means such as a bell 55 crank 34 which in turn is worked by a pull rod 35 and handle made accessible to the operator standing in front of the machine.

By pulling on the rod 35 the plunger 33 60 drives a small quantity of water downwardly past the valve box and through the pipe 25 into the boiler whereupon the water is sprayed from the nozzle 21 upon the hot inner wall of the boiler which instantly vaporizes the water into steam. The steam 65 rapidly flows upwardly and is diverted

downwardly in the direction of the arrows. The outer wall of the boiler being hot tends to further vaporize and superheat the steam in its downward movement until the steam flows under high pressure through the opening 13 into a steam receiving or spray chamber 37 and outwardly through perforations 38 onto the work.

70 Since the water tank swings with the press lever, no elbow water joint is required since 75 the pipe 25 is rigidly installed; and hence no packing glands are required making for simplicity in construction, operation and maintenance.

80 What I claim is:

1. An electric garment pressing machine comprising in combination cooperating pressing members, a lever by which a pressing member is moved in relation to the other, a water tank carried with the lever 85 above the latter's fulcrum point to balance itself thereabove, steam generating means inside the pressing member, a pipe connection made between the tank and generating means, and means for discharging water 90 from the tank to the pressing member.

95 2. An electric garment pressing machine comprising in combination cooperating pressing members, a lever by which a pressing member is moved in relation to the other, a water tank carried by the lever, steam generating means inside the pressing member, a pipe connection made between the tank and generating means, and a manually operated 100 pump for forcing a predetermined quantity of water from the tank into the pressing member.

105 3. An electric garment press comprising a head and buck, a lever adapted to open and close the press, a fulcrum shaft on which the lever pivots, a water reservoir balanced on the fulcrum shaft and adapted to oscillate therewith, a water tube connection running from the reservoir to one of the pressing members, and steam generating means in the 110 said pressing member by which the water is vaporized.

115 4. An electric garment press comprising a head and buck, a lever adapted to open and close the press, a fulcrum shaft on which the lever pivots, a water reservoir balanced on the fulcrum shaft and adapted to oscillate therewith, a water tube connection running from the reservoir to one of the pressing members, and an electric boiler 120 steam generating means in the said pressing member by which the water is vaporized.

125 5. An electric garment press comprising a head and buck, a lever adapted to open and close the press, a fulcrum shaft on which the lever pivots, a water reservoir mounted on the shaft and adapted to oscillate therewith, a water tube connection running from the reservoir to one of the pressing members, steam generating means in the said pressing 130 member

- members by which the water is vaporized, and a pump on the reservoir, a handle mounted on the pressing member and adapted to operate the pump.
5. An electric garment press head and steam generator, comprising a perforated press plate, a spray chamber adjacent the perforated press plate, said press head being provided with an opening therein leading 10 to the spray member, an apertured plug inserted in the opening, an electric water boiler mounted on the plug and removable from the press head with the plug, and means for supplying water to the boiler which produces 15 steam and discharges the same downwardly thru the apertured plug into the spray chamber.
6. An electric garment press head and steam generator, comprising a perforated 20 press plate, a spray chamber adjacent the perforated press plate, said press head being provided with an opening therein leading to the spray chamber, an apertured plug inserted in the opening, an electrically heated 25 cup mounted in the plug, and means for spraying water into the cup thereby generating steam which discharges through the apertured plug into the spray chamber.
7. An electric garment press head and steam generator, comprising a perforated 30 press plate, a spray chamber adjacent the perforated press plate, said press head being provided with an opening therein leading to the spray chamber, an apertured plug inserted in the opening, an electrically heated 35 cup mounted in the plug, and means for spraying water into the cup thereby generating steam which discharges through the apertured plug into the spray chamber.
8. An electric garment press and electric 40 steam generator therefor comprising a pressing member provided with a spray chamber, and provided with a foraminous pressing face through which steam is ejected onto the work, a closed bottom cup, electrical heating means encased in the cup wall, water spray means in the cup, means for forcing water to the spraying means, an opening underneath the cup leading to the spray chamber, and a steam dome placed over the cup and opening which directs the steam 45 downwardly toward the spray chamber as it issues from the cup.
9. An electric garment press and electric 50 steam generator therefor comprising a pressing member provided with a spray chamber, and provided with a foraminous pressing face through which steam is ejected onto the work, a closed bottom cup, electrical heating means encased in the cup wall, water spray means in the cup, a pump arranged 55 to force water to the spraying means, an opening underneath the cup leading to the spray chamber, a steam dome placed over the cup and opening which directs the steam 60 downwardly toward the spray chamber as it issues from the cup.
10. An electric garment press and electric 65 steam generator therefor comprising a pressing member provided with a spray chamber, and provided with a foraminous pressing face through which steam is ejected onto the work, a closed bottom cup, electrical heating means encased in the cup wall, water spray means in the cup, means for forcing water to the spraying means, an opening underneath the cup leading to the spray chamber, a steam dome placed over the cup and opening which directs the steam 70 downwardly toward the spray chamber as it issues from the cup, said pressing member being provided with an opening in the back face thereof opposite the foraminous pressing face, a plug upon which the aforesaid cup and steam dome are mounted, and said plug being installed in aforesaid opening of the pressing member.
11. An electric garment press and electric 75 steam generator therefor comprising a pressing member provided with a spray chamber, and provided with a foraminous pressing face through which steam is ejected onto the work, a lever adapted to open and close the press, a closed bottom cup, electrical heating means encased in the cup wall, water spray means in the cup, an opening underneath the cup leading to the spray chamber, a steam dome placed over the cup and opening which directs the steam 80 downwardly toward the spray chamber as it issues from the cup, a water reservoir fixed on the lever to swing up and down therewith, and means for forcing water from the reservoir to the electrically heated cup.
12. A press comprising a jaw provided 85 with a central aperture, supporting means secured in the aperture, an electrically heated receptacle mounted on the supporting means and having an opening out through which steam flows, means for supplying water to the receptacle for conversion into steam, and a steam dome disposed over the receptacle enclosing the aperture to direct steam from the receptacle through 90 the aperture, and said jaw being provided with a perforated steam spray chamber connected with the aperture.
13. An electric water boiler and steam generator and press jaw comprising in combination, a pressing plate having a foraminous 95 pressing surface and having a spray chamber, a base on which the boiler parts are assembled, said base being centrally apertured, means associated with the pressing plate and base whereby the said base is anchored to the plate with its aperture leading directly into the spray chamber, supporting means secured in the plug aperture, an electrically heated receptacle mounted on the supporting 100 means and having an upper opening out through which steam flows, means for supplying water to the receptacle for conversion into steam, a steam dome disposed over the steam generating receptacle enclosing the plug aperture, and said dome being adapted to direct the steam downwardly from the generating receptacle through the plug aperture and into the spray chamber.
14. A press comprising in combination, 105

- cooperating press jaws and operating means therefor, a water boiler, means to heat the water boiler, a supporting device attached to the boiler and press jaw to hold the water 5 boiler in spaced relation on and to one of the press jaws, said supporting means providing an air space between the boiler and press jaw, means to supply water to the boiler, said jaw being provided with a steam receiving chamber, and means to direct steam 10 from the boiler through the air space to the steam receiving chamber.
15. A press comprising in combination, cooperating press jaws and operating means therefor; one of said press jaws being provided with an opening, and with a steam receiving chamber; a dome disposed over and enclosing the opening, a steam generator mounted inside the dome adjacent the opening, and water force feed means connected 20 with the steam generator.

16. A press comprising in combination, cooperating press jaws and operating means therefor, a water receptacle carried on one of the jaws, means to convey water into the closed bottom of the receptacle to be vaporized inside the receptacle, heating means to maintain the receptacle at high temperature inside and outside thereof, the upper end of the receptacle being open to permit steam to flow therefrom; a dome disposed over the receptacle, close to the upper end thereof and close to the outer surface thereof, and thereby forming a restricted steam passage 25 downwardly alongside the receptacle causing steam to be superheated as it passes alongside the outer wall of the receptacle; and said jaw being provided with a steam receiving chamber into which the superheated steam flows. 30

In testimony whereof I affix my signature.
JAMES C. LEDBETTER. 40
